MEDICAMENT APPLICATOR

Milton J. Cohen, Washington, D. C.

Application July 31, 1959, Serial No. 176,904

7 Claims. (Cl. 128—184)

1

The present invention relates to a medicament applicator and more particularly to a medicament applicator intended for the treatment of diseases of the female genital organs.

Prior medicament applicators of the foregoing type have previously been made in the form of a douche having a nozzle for insertion in the vagina and a flexible container having therein a mixture of water and medicine which is adapted to pass through the nozzle under slight pressure for treatment of the genital organs. Other applicators have merely consisted of a nozzle through which a small amount of medicine could be applied to the interior of the vagina.

These prior applicators have had several serious disadvantages. For example, none of them makes provision for the fact that the vagina has a large number of folds therein which may be harboring disease within the interstices therebetween and that adequate treatment thereof requires that the vagina be distended during the treatment to fully eliminate such folds whereby the medication will come into contact with all areas of infection. A second disadvantage resides in the fact that where water is used for carrying the medicament to the affected parts, the operation is messy and requires bath and toilet facilities to be available. Other disadvantages are the inability to maintain safe sanitation of the types of applicators heretofore employed and to have prepared standard dosages of medicament available for immediate use.

The present invention corrects these deficiencies by providing an applicator having a nozzle for insertion within the vagina and a receptacle adapted to receive a renewable sealed capsule containing a compressed inert or harmless gas and a medicament in fluid form, the amount of medicament being standardized in dosage for the particular ailment to be treated. The capsule is provided with a frangible seal which is arranged to be in juxtaposition with a pin in the receptacle when the capsule is placed therein and the receptacle is so arranged that the seal in the capsule can be impinged upon the pin to puncture the seal when the treatment is to be applied. Upon puncturing the seal, the gas in the capsule passes through the nozzle carrying the medicament with it and inflates the vagina to eliminate the folds therein while forcibly causing the medicament to come into contact with all areas to be treated. The applicator is so designed that no leakage or a controlled amount of leakage of the gas occurs from the vagina until completion of the treatment whereupon withdrawal of the

2

applicator will permit the gas to escape while retaining the medicament which will have been trapped in the folds of the vagina by collapse of its walls.

5 The invention also contemplates an arrangement having two capsules within a receptacle on the applicator, one of which contains only gas and is employed for initially inflating the vagina and the second of which contains both gas and a medicament which are released to maintain the inflation of the vagina despite leakage while forcibly applying medicament thereto.

An object of the present invention is to provide a vaginal medicament applicator which has a high degree of sanitation.

Another object is to provide such an applicator whereby a standard prepared dosage of medicine may be applied.

A further object of the invention is the provision of a vaginal medicament applicator which will inflate the vagina and forcibly apply medicament thereto to insure effective medication thereof.

Still another object of the invention is to provide an applicator for treatment of diseases of the vagina which does not create a messy condition, is simple to use, and will therefore not distress the user.

Other objects and many of the attendant advantages of this invention will be readily appreciated as the same becomes better understood by reference to the following detailed description when considered in connection with the accompanying drawing in which like reference numerals 30 designate like parts throughout the figures thereof and wherein:

Fig. 1 is a view in perspective of a preferred form of the medicament applicator of this invention;

40 Fig. 2 is a sectional view of the applicator taken on the line 2—2 of Fig. 1 and with parts broken away;

Fig. 3 is a sectional view taken on line 3—3 of Fig. 2 looking in the direction of the arrows;

45 Fig. 4 is an enlarged partial sectional view showing the pin puncturing the frangible seal of the capsule;

Fig. 5 is a sectional view similar to Fig. 2 showing a modified form of the applicator;

50 Fig. 6 is a sectional view taken on the line 6—6 of Fig. 5 looking in the direction of the arrows; and

Fig. 7 is a view in perspective of the end of the applicator opposite the nozzle showing indicia to be employed in the modification of Fig. 5.

Referring now to the drawings, there is shown in Fig. 1 an applicator 11 having a body 12 made of a rigid material such as aluminum, Bakelite, polystyrene, or similar material. Attached to the body is a nozzle 13 held in place by any detachable fastening means such as a threaded connection 14. The nozzle is provided with a longitudinal passage 15 therethrough and small apertures 16 connected with the passage 15.

The body 12 is provided with a receptacle 17 therein open at one end but with external screw threads adapted to have screwed thereon a screw-cap 18 having an enlarged central aperture 19 therethrough. To seal the receptacle 17 against leakage of gas, a circular flexible gasket 21 made of rubber or other suitable material is arranged within the cap 18. The other end of the receptacle 17 is closed by a wall 22 having therein an aperture 23 surrounded by an upstanding cylindrical wall 24. Centrally supported within the aperture is an upstanding sharp-pointed pin 25 adapted to puncture a frangible seal 26 in the end of a capsule 27.

The capsule 27 contains a compressed gas such as carbon dioxide, nitrous oxide, argon, helium, or any gas not harmful to human tissues and also has therein a fluid medicament of the type useful for treating diseases of the vagina, the quantity of the medicament being an approved dosage for the particular disease to be treated. The medicament forms no part of the invention but may be a liquid, paste, or a fine powder as the case requires and must, of course, be compatible with the gas employed in the capsule.

The opposite side of the wall 22 has mounted thereon one part of the threaded connection 14 which has a longitudinal duct therein connecting the aperture 23 with the passage 15 of the nozzle 13.

The body 12 has integral therewith a cup-like member 28 lined with sponge rubber 29 or the like, the member 28 being shaped to intimately envelope the female genito-urinary area to prevent the escape of gas from the vagina when the applicator is in use. To further insure against the escape of gas, the body 12 is provided with an upstanding substantially cylindrical portion 31 adapted to partly enter the vagina and provide a tight fit thereby to seal it against gas leakage.

The manner in which the applicator of Fig. 1 is employed will now be briefly described. The cap 18 is first removed from the body 12 and a sealed capsule 27 containing the proper gas and medicament is inserted into the receptacle 17 after which the cap 18 and its associated gasket 21 are tightly screwed in place. The nozzle 13 is next inserted into the vagina to a point at which the cylindrical portion 31 of the body 12 seals the vagina and the cup-like member 28 snugly envelops the body.

The applicator is now properly in place for the treatment which is commenced by inserting a finger into the aperture 19 in the cap 18 and pressing the flexible gasket 21 into the dotted line position shown in Fig. 2 which forces the capsule 27 against the sharp pin 25 to cause it to puncture the frangible seal 26 in the capsule. The gas and medicament now are enabled to escape into the aperture 23 and the passage 15 to the apertures 16 from which they emerge into the vagina. The vagina is then distended by the gas to a point where the folds are eliminated therefrom and the medicament is enabled to forcibly contact all infected areas. Should the distention be so great as to be uncomfortable, a slight withdrawal of

75

the applicator will permit a small leakage of gas about the portion 31 and the member 28 which is allowed to continue until comfort is again restored. Upon completion of the treatment, withdrawal of the applicator will release all the gas and the vagina will return to normal leaving the medicament entrapped in its folds.

Referring now to Figs. 5, 6 and 7, a modified arrangement will now be described. As can be seen, the nozzle 13, member 28 and portion 31 are exactly the same as in the applicator of Fig. 2, the sole difference in the two forms residing in the body 12a.

The body 12a contains two receptacles 17a and 17b separated by a wall 32. One end of the body is adapted to be closed by a screw-cap 33, as in Fig. 1, having an aperture 34 therethrough and adapted to receive a flexible gasket 35 therein. The gasket may bear indicia thereon as indicated in Fig. 7 for a reason to be made clear herein-after.

The other end of the body 12a is closed by a wall 36 to complete the receptacles 17a and 17b. The receptacle 17a has an aperture 37 in the wall 36 and a pin 38 supported in the aperture for the same purpose as the pin 25 in Fig. 2. Receptacle 17b is similarly provided with an aperture and pin.

The receptacles 17a and 17b are adapted to receive capsules 39 and 41, respectively, the capsule 39 being filled with a gas under pressure of the type previously described and having a frangible seal. The capsule 41 contains a similar gas under pressure and any desired medicament in the proper dosage as in the case of capsule 27.

The manner in which the modification of Fig. 5 is employed will be readily apparent. After capsules 39 and 41 have been placed in receptacles 17a and 17b, respectively, the cap 33 and gasket 35 are tightened in position with the indicia on the gasket properly oriented over the capsules. The nozzle is next inserted in the vagina as described hereinbefore and, when in proper position, a finger is inserted in the aperture 34 of the cap 33 to deflect the gasket, as shown in Fig. 5, and cause the gas capsule 39 to impinge on the pin carried by the wall 36. The frangible seal of the capsule is thus punctured and the gas escapes into the nozzle 13 to cause distention of the vagina. After distention of the vagina, the finger in aperture 34 is shifted to cause deflection of the capsule 41 and puncturing thereof by the pin 38 to admit gas and medicament to the nozzle 13 and thence to the vagina. As before, excess pressure may be relieved by a slight withdrawal of the applicator and complete withdrawal thereof will permit the gas to escape and allow collapse of the vagina.

From the foregoing description, it is clear that the arrangement of Fig. 1 permits simultaneous distention and treatment of the vagina whereas the modified form of Fig. 5 allows distention to take place prior to the medication. It will be understood that if capsule 41 of Fig. 5 is employed alone without using capsule 39, the result will be similar to that of Fig. 1.

It will be apparent that the foregoing disclosure relates to only preferred embodiments of the invention and that it is intended to cover all changes and modifications of the examples of the invention herein chosen for the purposes of the disclosure, which do not constitute departure from the spirit and scope of the invention as set forth in the appended claims.

What is claimed is:

1. A medicament applicator comprising a gas-tight receptacle, a nozzle having an aperture communicating with said receptacle, a capsule containing a medicament and a gas under pressure within said receptacle, a pin in the receptacle for puncturing said capsule, and a flexible cap on said receptacle adapted to be displaced to cause said capsule to impinge upon said pin.

2. A medicament applicator comprising a gas-tight receptacle, a nozzle having an aperture communicating with said receptacle, a capsule containing a medicament and a gas under pressure within said receptacle, said receptacle having a plurality of compartments, a first capsule containing compressed gas in one compartment, 15 a second capsule containing a medicament and compressed gas in the other compartment, and means in said applicator for puncturing said capsules.

3. The applicator of claim 2 having a pin in each compartment for puncturing the capsule therein, and a flexible cap on said receptacle adapted to be displaced to cause said capsules to impinge on said pins.

4. The applicator of claim 3 in which said cap comprises a rigid circular element having a central aperture therethrough, and a flexible gasket within said element for sealing said cap to the receptacle, said gasket being displaceable through said central aperture.

5. A medicament applicator for treatment of the female genital organs comprising a gas tight compartment having an outlet, a capsule in the compartment said capsule containing a medicament and a compressed gas, manually operable means for puncturing the capsule, an elongated nozzle leading from the outlet of the com-

partment, and a flaring cup-like flange surrounding the nozzle and adapted to engage the body of the patient to prevent leakage of gas between the body of the patient and the applicator, said compartment being cylindrical and approximately coaxial with the nozzle and having an opening at its end opposite the nozzle for insertion of a capsule, and a flexible closure for said opening.

6. An instrument for injecting gas into cavities of the human body comprising a chamber having a nozzle at one end and an opening at the other for insertion of a container for a mixture of a medicament and a compressed gas, a closure for said opening having a flexible central portion, and means at said nozzle for puncturing the container when it is moved endwise by pressure on the flexible portion of the closure.

7. An instrument for injecting fluent medicament into body cavities comprising a chamber having a nozzle at one end and an opening at the other for insertion of a compressed gas container, puncturing means adjacent the nozzle, and a flexible closure for the opening positioned 25 to move the container toward the puncturing means upon pressure against said closure.
